Primary Examiner — W. A. Teddy Falloway*Assistant Examiner* — Rani J Abdallah(74) *Attorney, Agent, or Firm* — Sheridan Ross P.C.(57) **CLAIM**

The ornamental design for a bottle, as shown and described.

DESCRIPTION

FIG. 1 is a perspective view of a bottle;

FIG. 2 is a front plan view thereof;

FIG. 3 is a back plan view thereof;

FIG. 4 is a right side plan view thereof;

FIG. 5 is a left side plan view thereof;

FIG. 6 is a top plan view thereof; and,

FIG. 7 is a bottom plan view.

The broken lines of FIG. 7 show portions of the bottle which form no part of the claimed design. The dash-dot-dash line(s) of FIG. 7 define the bounds of the claimed design and form no part thereof.

1 Claim, 6 Drawing Sheets(56)
